ATTORNEYS

UNITED STATES PATENT OFFICE.

JOSEPH W. HELTZEL, OF WARREN, OHIO.

ROAD-BUILDING MACHINE.

1,380,379.

Specification of Letters Patent. Patented June 7, 1921.

Application filed March 11, 1920. Serial No. 364,958.

To all whom it may concern:

Be it known that I, JOSEPH W. HELTZEL, a citizen of the United States, and a resident of Warren, in the county of Trumbull and State of Ohio, have invented a certain new and useful Improvement in Road-Building Machines, of which the following is a specification.

My invention is an improvement in road building machines, and has for its object to provide a machine of the character specified, especially adapted for tamping brick and newly laid concrete, as for instance in brick paving, wherein a tamping member is provided of relatively large extent adapted to rest upon the surface of the pavement, and a ram contacting with such first named member to thoroughly tamp the brick or concrete in place, thus causing the same to 20 have a smooth surface.

In the drawings:—

Figure 1 is a top plan view of the improved machine,

Fig. 2 is a front view with the pavement 25 in section,

Fig. 3 is a section on the line 3—3 of Fig. 2, and

Fig. 4 is a partial perspective view of the tamping member.

In the present embodiment of the invention, a suitable frame 1 is provided of substantially rectangular formation, having intermediate the front and rear ends thereof a pair of laterally spaced cross bars 2. 35 Wheels 3 are provided for supporting the frame, the said wheels being journaled in the arms of yokes 4, whose bodies are secured to the underside of the frame at the corners thereof, and these wheels are flanged 40 to run upon rails 5 which are journaled upon opposite sides of the frame, as indicated at 6.

A suitable motor, indicated at 7 in the present instance, an internal combustion engine, is supported by the cross bars 2 at approximately the center of said bars, and the shaft of this motor is connected by gearing 8 with a shaft 9 journaled in bearings 10 on the cross bars. The said shaft has a 45 pair of cams 11, each cam being a disk having a hub rigidly secured to the shaft, and having a laterally extending marginal flange 12 at its outer face, which flange is open at one point, as shown at 13.

The ram is composed of a beam 14, having a channel-shaped reinforcing shoe 15

on its under edge, and this beam is held between a pair of channel plates 16, the said plates having their channels facing downwardly. The channel plates are connected at their edges by the channel plate 16 and at each cam a bracket 18 is secured to the plate 17. Each bracket carries a laterally-extending roller 19 which engages the flange 12 of the adjacent cam. The opening 13 in the flange of the cam ends at that portion of the flange 12 which is farthest from the center. The arrangement is such that when the ram rests upon the tamping member, that is when it is in its lowest position, the end of the flange 12 will engage beneath the roller and will gradually lift the ram until it again passes out at the opening 13, whose other end is at that portion of the flange which is nearest the shaft. Thus the rollers 75 and the ram will be lifted and will be permitted to drop once during the rotation of the shaft 9. The beam 14 is connected to the channel plates by bolts and nuts 20, and the said beam extends well below the lower 80 ends of the channel plates.

The case consisting of the elements 16 and 17 in which the tamping beam is mounted, has pivoted near its ends links 21, which are pivoted at their other ends to depending arms 22 from the frame. Thus the case is 85 swingingly supported and held from rearward movement with the cam. It will be understood that this beam may be constructed in the same manner as that shown in my co-pending application, Serial No. 364,958 filed March 11, 1920, to permit it to conform 90 with the crown of the road where used on a crowned road.

The tamping member is composed of a 95 series of plates 23 connected at one end by a cross plate 24, the plates 23 and 24 being rigidly secured together by bolts and nuts 25. The tamping member is connected at its front end by hinges 26 to a cross plate 27 100 carried by the arms of the forward yokes 4 and the underfaces of the plates 23 are reinforced, as shown at 28.

In use, the machine is drawn over the roadway moving on the rails with the tamping member sliding on the table, which may be covered with sand in the usual manner. As the machine travels, the shaft 9 is rotated by the motor and the ram is lifted and dropped a number of times per minute depending upon the revolutions of the shaft. At the point where the ram engages the

plates 23 they are reinforced by reinforcing plates 29. The ram strikes upon these reinforcing plates. In order to provide a smooth surface in front of the machine, a 5 smoothing plate 30 is supported just above the level of the track by means of arms 31 depending from the frame. When tamping newly laid brick, this smoothing plate is not required.

10 In operation, the machine is drawn over the road in any suitable manner, it being understood that the motor might be geared to the wheels 3 if desired. As the machine moves the tamping member moves in contact 15 with the pavement and the ram is lifted and permitted to fall heavily upon the tamping member. Thus the pavement is thoroughly tamped and surfaced.

In the usual method of finishing brick 20 paving, a roller is used, and the said roller presses a brick first on one edge, then in the center, and then on the opposite edge, thus causing the foundation for the brick to have a convex top surface. That is, the brick is 25 rocked by the roller, and the supporting surface for the brick is shaped by the rocking of the brick. The present invention eliminates this undesirable shape in the brick foundation, tamping the brick as a whole 30 firmly and solidly downward, so that there is no tendency to rock.

Having thus described my invention, I claim:

1. A machine of the character specified 35 comprising a wheel supported frame, a tamping member hinged to the front of the frame and adapted to slide upon the pavement as the frame moves over the roadway, a ram for striking said tamping member transversely 40 of the length thereof and approximately at the center, and means for lifting the ram and permitting it to fall upon the tamping member, said tamping member comprising a series of longitudinally extending plates arranged alongside each other and spaced 45 apart slightly from each other and rigidly connected at their rear ends, said plates being hinged at their forward ends to the plate and being reinforced on their under faces.

2. A machine of the character specified 50 comprising a wheel supported frame, a tamping member hinged to the front of the frame and adapted to slide upon the pavement as the frame moves over the roadway, a ram for striking said tamping member 55 transversely of the length thereof and approximately at the center, and means for lifting the ram and permitting it to fall upon the tamping member, the ram comprising a beam extending transversely of 60 the tamping member, a case for the beam in which it is adjustably mounted, means for swingably connecting the case to the frame to permit said case to swing upwardly and downwardly.

3. A machine of the character specified comprising a wheel supported frame, a tamping member hinged to the front of the frame and adapted to slide upon the pavement as the frame moves over the roadway, 70 a ram for striking said tamping member transversely of the length thereof and approximately at the center, and power operated means for lifting the ram and permitting it to fall upon the tamping member.

4. A machine of the character specified comprising a wheel supported frame, a tamping member hinged to the frame at the front thereof and below the level of the frame to move upon the pavement to be 80 tamped, a ram for engaging the tamping member, and power operated means for lifting and dropping the ram at rapid intervals, 85 said lifting means comprising a shaft, cam disks on the shaft having laterally extending flanges eccentric to the shaft, said flanges being cut away between the highest and lowest points at one side of the shaft, the ram having rollers engaged within the flanges.

5. A machine of the character specified 90 comprising a wheel supported frame, a tamping member hinged to the frame at the front thereof and below the level of the frame to move upon the pavement to be tamped, a ram for engaging the tamping 95 member, and power operated means for lifting and dropping the ram at rapid intervals.

JOSEPH W. HELTZEL.
